UNITED STATES PATENT OFFICE.

ALBERT BRINKMANN, OF PHILADELPHIA, PENNSYLVANIA.

TONGS.

SPECIFICATION forming part of Letters Patent No. 738,154, dated September 8, 1903.

Application filed May 14, 1903. Serial No. 157,132. (No model.)

To all whom it may concern:

Be it known that I, ALBERT BRINKMANN, a citizen of the United States, residing at Philadelphia, Pennsylvania, have invented certain new and useful Improvements in Tongs, of which the following is a specification.

My invention relates to improvements in tongs designed more particularly for removing cinders and the like from stoves, but useful also in any situation where fire-tongs are desirable.

The object of the invention is to provide a simple and effective device which will be economical to manufacture, durable in use, and will not be liable to get out of order.

To this end the invention comprises the particular construction hereinafter described, and particularly pointed out in the claims.

The invention is illustrated in the accompanying drawings, in which—

Figure 1 is a side elevation. Fig. 2 is a view at right angles to Fig. 1. Fig. 3 is a section on line xx of Fig. 1. Fig. 4 is an edge view of modified form of grip, and Fig. 4^a a face view of the same. Fig. 5 is a sectional view of a further modification, and Fig. 5^a a face view of the same.

According to my invention I make the body of the tongs out of a single piece of steel or like wire. The wire is coiled upon itself at the center one or more times, as indicated at 1, and thence is carried forward in two parallel portions 2, which form the handle or grasping portions. At the extremity of each handle the wire is bent outwardly, as at 3, to form a shoulder and then is carried across to and around the opposite member, as indicated at 4, this portion 4 being inclined backwardly, so as to bring it in rear of the shoulder 3 on the opposite member. After passing around the opposite member 2 the wire is bent back upon itself, as indicated at 5, the space between the portions 4 and 5 of one arm of the tongs forming a guide for the corresponding portions of the other side or arm. The portions 5 are brought into proximity to each other, from which point the wire is carried forward in two parallel members 6, the outer

ends of which are provided with suitable gripping devices. I prefer that these devices 50 shall be in the shape of concave disks 7, of metal, riveted to the flattened ends of the wires, and the edges of these disks are preferably toothed, as indicated at 8, the teeth of one disk being arranged opposite the spaces 55 between the teeth of the opposite disk. Instead of providing disks on the ends of the arms the ends of the arms may be bent into loops, as indicated at 10 in the modified form.

By this construction it will be seen that I 60 provide an extremely simple construction in which the number of parts are reduced to a minimum and which may be produced at an extremely low cost. There is absolutely nothing about the tongs to get out of order and 65 no pivotal joints to wear out. Further, by bringing the wires together in proximity to the handle and then extending them forward parallel to each other the tongs may be inserted into any stove-opening, no matter how 70 narrow, for the removal of cinders and the like.

If desired, the end grips might be secured to the looped ends of the arms, as shown in Fig. 5, the grip being formed of strips 11 of 75 sheet metal bent into cylindrical form and each having one edge 12 bent around the corresponding loop and the other toothed, as shown at 13.

Having thus described my invention, what 80 I claim is—

1. A pair of tongs comprising a single piece of wire having a coiled central portion and substantial parallel handle portions extending therefrom, the wire at the extremity of 85 each handle portion being carried across to and around the opposite handle portion and then back to the center from which central point both wires extend forward substantially parallel to each other, and a gripping device 90 at the outer ends of said wires, substantially as described.

2. A pair of tongs comprising a single piece of wire having a coiled central portion and parallel handle portions extending therefrom, 95 the wire at the extremity of each handle por-

tion being bent outwardly to form a shoulder, thence across to and in rear of the shoulder of the opposite handle portion and then back to the center, from which center point both 5 wires extend forward parallel to each other, and gripping devices carried at the outer ends thereof, substantially as described.

In testimony whereof I affix my signature in presence of two witnesses.

ALBERT BRINKMANN.

Witnesses:

ARNOLD NACKE,
FRANK D. NACKE.
